UNITED STATES PATENT OFFICE.

JAMES DWYER, OF DETROIT, MICHIGAN.

DESIGN FOR A COOKING-STOVE.

SPECIFICATION forming part of Design No. 19,415, dated November 12, 1889.

Application filed August 10, 1889. Serial No. 320,419. Term of patent 7 years.

To all whom it may concern:

Be it known that I, JAMES DWYER, a citizen of the United States, residing at Detroit, county of Wayne, State of Michigan, have 5 invented a certain new and useful Design for a Cooking-Stove; and I declare the following to be a full, clear, and exact description of the invention, such as will enable others skilled in the art to which it pertains to 10 make and use the same, reference being had to the accompanying drawing, which forms a part of this specification.

The drawing is a view in perspective embodying my invention.

15 The design which is the subject-matter of this application embodies the following elements:

A represents the legs, ornamented from top to toe with embossed scrolls.

20 B, C, D, and E are plain bands.

F is the oven-door, ornamented with fan-shaped figures at the four corners, the door having a plain surface and of swelled form. There is also an ornament in the form of a 25 rosette embracing the handle. Straight stems project therefrom horizontally for a certain distance and then terminate in scrolls and leaves. The fuel-door G is similarly decorated with fan figures at the four corners and with 30 a scroll-work springing from the handle and extending thence across the door, the door having a general plain surface and of swelled form. Beneath the reservoir there is a section H, of swelled form, with fan figures at its 35 corners, and with a spray of scroll-work starting from its lower edge and extending over

part of its surface. Beneath this is a bracket J, ornamented at its edge with the plain band E and with the upright parallel moldings j, curved at the top, as shown. 40

What I claim is—

1. The design for a stove, consisting of the legs A, ornamented from top to toe with embossed scrolls, oven-door E, fuel-door G, and section H, all of swelled form, with fan ornaments at the four corners and a scroll figure on the face, plain bands B C D E, and molded section j, substantially as described and shown. 45

2. In the design for a stove, the oven-door F, 50 of swelled form, with fan ornaments at its corners, a rosette surrounding the handle, stems leading horizontally therefrom across the door and terminating in a spray of scrolls and leaves, substantially as described and shown. 55

3. In the design for a stove, the stove fuel-door G and section H, each with fan ornaments at the four corners, a large spray of scrolls and leaves projecting over the general surface, said general surface being of swelled 60 from, substantially as shown.

4. In the design for a stove, the bracket-section J, provided with an ornamentation consisting of parallel moldings j, curved at their tops, substantially as shown. 65

In testimony whereof I sign this specification in the presence of two witnesses.

JAMES DWYER.
